United States Patent

Des. 242,450
Patented Nov. 23, 1976

242,450

WRITING PEN

Rudi Jahraus, Keltern-Ellmendingen, Germany, assignor to Moriz Hausch GmbH

Filed Apr. 21, 1975, Ser. No. 569,957

Term of patent 14 years

Int. Cl. D19—06

U.S. Cl. D19—45

FIG. 1

FIG. 2

FIG. 3

FIG. 4

FIG. 5

FIG. 1 is a top plan view of a writing pen showing my new design;

FIG. 2 is a front elevational view;

FIG. 3 is a right side elevational view with the point in an extended position;

FIG. 4 is a rear elevational view of FIG. 2; and

FIG. 5 is a left side elevational view thereof.

I claim:

The ornamental design for a writing pen, substantially as shown and described.
